Ohio, a corporation of Ohio, as trustee

Application June 7, 1928, Serial No. 283,585.

8 Claims. (Cl. 15—13)

This invention relates to cleaning tools adapted to be used in connection with pneumatic or suction cleaners which are electrically driven, and more particularly in connection with air-method cleaners known commercially under the registered trade-mark "Air-Way". The invention relates more in detail to attachments for "Air-Way" cleaning tools of the type described in my application for Letters Patent Serial No. 10 15,529, filed March 14, 1925.

The objects of the invention are to provide an electrically operated attachment to be connected to the floor tool and operated by an electrical extension cord from the motor, to improve the action 15 of the floor tool by vibrating a portion of the face of the tool, to make and combine an electrical buzzer with such floor tool when operated on stationary plants; and other objects as may appear from this specification and may be 20 pointed out in the claims.

To these ends, the invention consists of the design, construction and arrangement of parts and elements as shall now be described and as are illustrated in the drawing, in which:

25 Figure 1 is a plan view with sections taken on the lines C—D and E—F of Figure 3.

Figure 2 is a reduced size view in perspective of one end of the buzzer attachment, a similar end being broken away.

30 Figure 3 shows a section taken on the line A—B of Figure 1.

Figure 4 is a greatly reduced view in perspective of an "Air-Way" cleaner with one of the buzzer attachments connected to the tool there- 35 of.

Similar characters of reference refer to like and corresponding parts in the several figures.

Referring to the drawing, the body of the floor tool 1, having spring support rollers 2, 2 40 designed to hold it above the carpet to be cleaned, is to be supplied with air suction through the pipe 3. An "Air-way" cleaner tool is provided with channels to hold strokers as 4 but when the present improvement is to be used one of the 45 strokers 4' is to be removed and mounted on the vibrator arm 5 carrying the armature 6 and the channel socket 7, in the latter of which the stroker 4' is held securely and to be vibrated so that its lower lip portion shall buzz or beat the 50 carpet which is sucked up against it by the in-rushing air. A rubber substitute strip 4'' is placed in the channel of the floor tool from which the stroker has been removed and its lower edge is arranged to impinge on the upper side of the tilted stroker 4', making a seal against leakage 55

but being sufficiently resilient to permit sufficient small vertical vibrations of the stroker 4'.

The vibrations are produced by the electromagnetic buzzer in the encasements 8, 8, carrying a common plate or vibrator arm 5, screwed to 5 the encasement walls at 9, 9, etc. Either type, the current breaker, or the alternating current type buzzer can be used, but the one here shown is an alternating current type buzzer in which the armature strain is regulated by the extension 10 springs 10, 10, which springs are to be varied in tension by the knurled nuts 11, 11, according to the power and current applied through the coils 12, 12, etc. which may be wound to work in series or in parallel, but are here shown as in 15 two pairs, each pair in series but all designed to act in unison on the common arm 5, to lugs of which the springs 10, 10, are hooked at 10', 10'. The portions to which the coil cores are attached at 12', 12' are the top covers of the 20 encasements 8, 8, connected to the arm 5, which not only vibrates but extends through under the pipe 3 the whole length of the device, so that clamps 13, 13 which are welded to the sides of the encasements 8, 8, at 8', 8', will hold the 25 entire device firmly in position when the hooks 13', 13' are caught over the body of the tool and hooks 13'', 13'' of the clamps are caught under the edge of the tool channel as shown. A rubber guard 8'' surrounds the base of encase- 30 ment 8.

The vibration of the arm 5 of the device is effected by current from the cord 14 which may lead from any electrical source, but is here shown as coming from an extension from the motor of 35 an "Air-Way" cleaner 15 which in turn receives its current from a cord 16, the cords 14' and 14' leading to the coils, being merely extensions of the lead 14.

The cleaner with the attachment in place is to 40 be used by moving back and forth over the carpeted floor. As the in-rushing air lifts the carpet against the strokers, the buzzing or rapid vibrations of the lip or stroker 4' imparts its vibrations to the lifted carpet dislodging imbedded 45 particles of dust which plain air currents will not affect. When the tool is pressed down upon the floor between the spring support rollers, the lip or stroker 4' will of course beat upon the flat lying carpet upon the floor.

Having thus described the invention and the operation in the present embodiment thereof, I do not wish to be confined to the details as shown since many of them may be greatly modified without departing from the spirit of the invention. 50 55

I claim broadly:

1. An attachment unit for a cleaning tool having a floor engaging lip, comprising a casing, an electro-magnet carried by said casing having a 5 vibrator arm also carried by the casing and carrying another lip for said tool, means for detachably connecting the casing to the tool and means for bringing electric current to the electro-magnet.
- 10 2. In combination with the floor tool of a suction cleaner having an unobstructed suction inlet, a vibrator unit detachably secured to the floor tool comprising a casing, an electro-magnet and vibrator arm carried by the casing, spring 15 clips for detachably connecting the casing to the exterior of the floor tool, and a floor-engaging lip carried by the vibrator arm.
- 20 3. In combination with a suction cleaner having an elongated nozzle with an unobstructed suction inlet, a vibrator unit detachably connected to the nozzle externally of the suction inlet, comprising a pair of casings each carrying an electro-magnet, a common vibrator arm carried jointly by both of the casings, a floor-engaging lip 25 operated by the vibrator arm, and clamps carried by said casings for detachably securing said unit to the nozzle.
- 30 4. A supplemental unit for attachment to the floor tool of a suction cleaner, comprising a casing, an electric current consuming device located within the casing, and spring clips carried by the casing for detachably securing the casing to the outside of the floor tool.
- 35 5. In combination with a floor tool for a suction cleaner, having an elongated suction nozzle; a supplemental unit for attachment to the floor tool, comprising a casing, an electric current consuming device located within the casing, and spaced spring clips carried by the casing and fitting over the exterior of said nozzle for detachably connecting said supplemental unit to the floor tool.
6. In a pneumatic cleaner, an elongated suction nozzle, supplemental non-metallic lip members carried by the nozzle along the longitudinal edges thereof and defining a mouth, a vibrator actuating unit connected to the nozzle externally and in rear thereof, said unit including an electromagnet independent of the suction producing means having a vibrating armature, and an oscillating element actuated by said armature and cooperating with the nozzle in the cleaning operation, said element having a surface engaging portion extending past the inner edge of the rear lip.
- 10 7. In combination with a suction cleaner having an elongated nozzle, a vibrator actuating means mounted externally and in rear of the 20 nozzle, and including a pair of spaced electromagnet carrying units, one mounted adjacent each end of the nozzle, each unit being provided with means for attachment to the nozzle, electromagnets carried by said units, and surface engaging vibrator means actuated by said electromagnets and cooperating with the nozzle in the 25 cleaning operation.
8. In a pneumatic cleaner, an elongated nozzle having a suction inlet, a vibrator actuating unit 30 connected at the rear of the nozzle externally of the suction inlet, and including a pair of spaced electromagnets, one mounted adjacent each end of the nozzle, and a surface agitating means actuated by said electromagnets and cooperating with 35 the nozzle in the cleaning operation.

DANIEL BENSON REPLOGLE.
